DESIGN FOR A SCARF OR SIMILAR ARTICLE

Muriel Gross, New York, N. Y.

Application January 13, 1948, Serial No. 143,702

Term of patent 7 years

(Cl. D3—12)

To all whom it may concern:

Be it known that I, Muriel Gross, a citizen of the United States of America, residing in New York city, county of New York, and State of New York, have invented a new, original, and ornamental Design for a Scarf or Similar Article, of which the following is a specification, reference being had to the accompanying drawing, forming part thereof, wherein the figure is a plan view of a scarf, showing my new design.

I claim:

The ornamental design for a scarf or similar article, substantially as shown.

MURIEL GROSS.
